UNITED STATES PATENT OFFICE.

MATTHEW BLOOMER, OF EAST BRISBANE, QUEENSLAND, AUSTRALIA.

APPARATUS FOR MANUFACTURING ROLLER AND SEMIROLLER CHAINS.

Application filed September 23, 1925, Serial No. 58,181, and in Australia September 26, 1924.

This invention relates to an improved apparatus for manufacturing roller and semi-roller chains and the object of the invention is to provide means for collating the different parts and for quickly assembling the same with accurate adjustment.

The apparatus consists of two devices for collating the parts and a device for assembling the parts made of cast metal with the 10 beds recessed to receive the parts, and provided with movable members for holding the parts together and locking levers therefor, said beds being formed integral with base plates which latter are adapted to be 15 fastened to a bench.

To fully describe the invention reference is now made to the accompanying drawings in which:—

Fig. 1, is a plan of the primary collating 20 device shown closed.

Fig. 2, is a plan of the secondary collating device shown open with the side cheek of a link in position.

Fig. 3, is a perspective view of the secondary 25 collating device open showing the side cheek and the distance bushes of a link.

Fig. 4, is a plan of the assembling device, open.

Fig. 5, is a perspective view of the same. 30 Fig. 6, is a broken perspective view of the bed.

Fig. 7, is a broken perspective view of the slide block.

Fig. 8, is a perspective view of one cheek 35 and the distance bushes.

Fig. 9, is a perspective view of a link complete.

Fig. 10, is a plan of one cheek and elevation 40 of a distance bush.

Fig. 11, is a plan view showing two bushed links, and one incomplete rivet link, before assembling.

Fig. 12, is a plan view showing two bushed links and one rivet link assembled. 45

In Figs. 1, 2, and 3, 1 is the base plate having slots 1^a at the end for bolting down on to a bench.

2 is the bed of the device which as shown 50 in Figs. 2 and 3 is recessed to receive the side cheeks of the link while the bed in Fig. 1 is plain.

The bed is formed integrally with a superimposed solid side member 3; in Figs. 2 and 3 they are rabbeted on the underside to 55 accommodate the cheeks of the links; on to the top of the side member is fitted plate

4 for holding the cheeks of the links in accurate position and the solid side member 3 in Fig. 3 is vertically grooved which together with vertical grooves 5^a in the hinged 60 jig 5, Fig. 3, hold the rivets 8^a in accurate position.

5 in Figs. 1, 2 and 3 is hinged jig and is locked by an eccentric lever 6, while the underside of the solid member 3 in Figs. 2 65 and 3 is rabbeted. 7 are the side cheeks of the links and 8 the shouldered distance bushes and 8^a the rivets in Fig. 3.

In Figs. 4 and 5 which illustrate the assembling device 1 is the base plate, 2 the 70 bed, 3 the superimposed solid side member fitted with plate 4 for holding the cheeks of the links in accurate position. 9 represents a groove in the bed to accommodate the end of the rivets.

The bed is slotted on one side as indicated at 2^a in which is fitted a spiral spring 10; a slide block 11 formed integral with a lug 11^a fits into the slot 2^a said slide block locked by the eccentric lever 6. 12 is a stop to arrest 80 the movement of the slide block 11.

The solid member 3 is rabbeted on its underside to accommodate the cheeks of the links.

In using the invention two shouldered 85 distance bushes are put in the primary collating device which is then closed by the eccentric lever 6, a cheek is then placed on the shouldered distance bushes and pressed by a plunger to fix the same together, the combination is then removed, reversed and placed in the secondary collating device which is then closed and locked by the eccentric lever and a cheek placed on to the shouldered distance bushes and pressed by a 90 plunger which completes one bushed link.

To make a rivet link, rivets are placed in a similar collating device as used for the bushed links with the exception that the holes in same for holding the rivets are 95 smaller, a cheek placed on top and pressed by a plunger, when one half of a rivet link is made.

To assemble the bushed and rivet links 100 to form a chain a bushed link is placed on each rivet of the rivet link, then placed in an assembling device illustrated by Figs. 4 and 5 and a cheek placed on top of the rivets and pressed by a plunger which completes a 105 length of chain consisting of a rivet link and two bushed links, the operation is repeated 110 to make a continuity of the chain, the bushed

links being the internal links and the rivet links the external links.

The slide block having a forward eccentric movement clamps the chain in the assembling device.

After the chain is assembled, the links are riveted in a machine.

What I claim as my invention and desire to secure by Letters Patent is:—

- 10 Apparatus for manufacturing roller and semi-roller chains including a base plate, a bed integral therewith, a side member integral with the upper surface of the bed and recessed adjacent the bed to accommodate portions of the link, a jig movably mounted on the upper surface of the bed for coacting

with the stationary side member and also recessed adjacent the base to accommodate the remaining portion of the link engaged with the side member, the side member and jig being also provided with means for receiving and clamping the pins of the link when the jig is moved towards the side member, plates for clamping other links secured to the upper surface of the side member and jig one of said plates being recessed, and a rotatably mounted locking lever for association with the jig, substantially as and for the purposes set forth.

In testimony whereof I affix my signature.

MATTHEW BLOOMER.
